[57] CLAIM

The ornamental design for an exercise platform, as shown and described.

DESCRIPTION

FIG. 1 is a perspective view of a exercise platform showing our new design;

FIG. 2 is an exploded perspective view thereof;

FIG. 3 is a top plan view thereof;

FIG. 4 is a front elevational view thereof, the rear view appearing the same;

FIG. 5 is a left side elevational view of FIG. 3, the right side view being a mirror image;

FIG. 6 is a bottom plan view thereof;

FIG. 7 is a top plan view of the lower base portion of the exercise platform as shown in FIG. 1; and,

FIG. 8 is a bottom plan view of the upper portion of the exercise platform.
